UNITED STATES PATENT OFFICE

94,085

DESIGN FOR AN ADVERTISING CARD

Arthur P. Izard, Chicago, Ill., assignor to National Tailoring Company, Chicago, Ill.

Application October 8, 1934, Serial No. 53,515

Term of patent 14 years

To all whom it may concern:

Be it known that I, Arthur P. Izard, a citizen of the United States, residing at Chicago, in the county of Cook and State of Illinois, have invented a new, original, and ornamental Design for Advertising Card, of which the following is a specification, reference being had to the accompanying drawing, forming part thereof.

The figure is a plan view of an advertising card showing my new design a part of the card being broken away for convenience in illustration. The figure of the sheep or ram is shown by flat printing on the card.

I claim:

The ornamental design for an advertising card as shown and described.

ARTHUR P. IZARD.
